HANGABLE TRANSPARENT DISPLAY PACKAGE

William K. Morgan, Coshocton, Ohio, assignor to Pretty Products, Inc., Coshocton, Ohio, a corporation of Ohio

Filed Jan. 11, 1968, Ser. No. 10,126

Term of patent 14 years

Int. Cl. D9—04

U.S. Cl. D9—191

FIG. 1 is a front elevation of a hangable transparent display package showing my new design;

FIG. 2 is a rear elevation thereof, the hook being rotated 90 degrees;

FIG. 3 is a transverse sectional view thereof on an enlarged scale taken along line 3-3 of FIG. 1; and

FIG. 4 is a longitudinal sectional view thereof in an inverted position on an enlarged scale taken along line 4-4 of FIG. 1.

I claim:

The ornamental design for a hangable transparent display package, substantially as shown.
